SHINGLE

Albert Horowitz, Pittsburgh, Pa.

Application February 8, 1932, Serial No. 591,596

2 Claims. (Cl. 108—8)

This invention relates to shingles, and particularly to shingles simulating and having the appearance of brick and shaped so that they may be applied to a wall as veneer covering to simulate a brick wall.

One object of the invention is to provide a brick shingle of this type which may be easily and readily applied to a wall, and of such construction that will permit shingles to be co-operatively disposed and fitted together to cover the wall.

Another object of the invention is to provide a shingle of the foregoing character made of material resistant to weather, water, and fire such as asbestos or other ingredients having similar resistant characteristics.

In one form of the invention which I describe herein, the completed shingle is made to embody a plurality of portions simulating bricks separated and spaced from each other lengthwise but joined along their side edges to a base strip which serves as the means for securing the entire integral unit to the wall upon which the covering is to be disposed. In one form of my invention the continuous base strip is provided with spaced, raised, interlocking bars that fit into the spaces between the brick portions of a shingle to be placed in position on top of the continuous supporting strip. In this modification the raised interlocking bars simulate, and create the impression of, a cementing mortar between the bricks. In order to maintain this impression of a cementing mortar between adjacent shingles, the continuous base strip on each shingle is provided with a raised section running longitudinally along the edges of the brick-simulating portions.

In another modification the locating and interlocking bars are not employed on the base strip, but the brick portions are connected lengthwise by corresponding portions to simulate mortar between the bricks.

The construction of the shingles and the manner in which they are assembled are illustrated in the accompanying drawing, in which

Figures 1a, 1b and 1c are arranged in a vertically superposed position to show what may be considered a vertically exploded view of three rows of the brick shingles that are to be joined together;

Figure 2 represents an end elevational view of the three elements shown in Figures 1a, 1b and 1c;

Figure 3 represents a sectional view through the three elements of the component Figures 1a, 1b and 1c, taken along the line 3—3 in those figures;

Figure 4 is a plan view of the top shingle unit shown in Figure 1a;

Figure 5 is a bottom view of the lower shingle unit shown in Figure 1b;

Figures 6, 7 and 8 are plan, front and bottom elevational views of a modified form of the shingle;

Figure 9 is an end elevational view of the shingle in Figure 7;

Figure 10 is a sectional view taken through the shingle in Figure 7 along the line X—X; and

Figure 11 is a perspective view showing the manner in which the shingle elements are to be assembled.

As shown in the drawing, a finished, complete shingle 1 comprises a plurality of brick-simulating portions 2 spaced or separated from each other longitudinally by narrow spaces 3 and joined along their inner lengthwise edges to a continuous base or nailing strip 4 that is provided with a plurality of holes 5 by means of which the strip may be nailed in position upon the wall that is to be covered by the brick-simulating shingles. The shingle is provided with a longitudinally running strip 6 slightly below or behind the plane of the front surfaces of the brick portions 2. This strip 6 is colored and positioned to simulate the exposed surface or edge of a layer of cementing mortar between layers of brick. In order to interlock and properly locate adjacent and cooperating shingles, interlocking bars 7 are provided on the continuous base or nailing strip 4 and these locating bars 7 are raised or extend forward from the front surface of the base 4 so that the front or top surfaces of the locating bars 7 are in the same plane as the front surface of the mortar simulating strip 6. These locating and interlocking bars also serve to simulate mortar between the bricks where the bars are located.

As may be seen upon reference to the end views as shown in Figure 2, the rear surface of the brick-simulating portions 2 is raised or extends forwardly of the plane of the rear surface of the base 4, a distance corresponding to the thickness of the base strip 4 so that the brick portions of one shingle strip may rest upon and be supported by the base strip 4 of an adjoining or lower shingle.

In Figures 7, 8 and 9 I have illustrated a modification similar to that shown in the previous figures except that the intermediate sections or portions of the base or nailing strip between the interlocking bars 7 are removed.

In a further modification which I consider

within the scope of the present invention, the interlocking bars 7 are not provided on the base strip 4. In that modification, the base 4 is of constant thickness throughout its length and serves merely as a nailing strip to support the brick portions attached to it and as a base for brick portions of an adjoining or superposed shingle. Instead of the spaces 3 between the brick portions 2, integral fillers are provided 10 between the bricks, extending from the plane of the rear surface of the brick portions 2 to a height or distance forward corresponding to the location of the front plane of the mortar strip 6, in order to give the impression of a mortar cement between the ends of the bricks. 15

The manner in which the shingles of the first modification are interlockingly fitted together, where the interlocking and locating bars 7 are employed, is illustrated in the schematic showing 20 in Figure 11. In that case the lower shingle is placed in position first and then the upper shingles are fitted over the lower shingles in turn, and nailed in position.

For the bottom row of such a wall, the spaces 25 between the bricks may be filled in any suitable manner or the brick portions may be sawed off the base strip so that only the base strip will be available as a locating base for the shingles to be superimposed thereon. This arrangement, of course, is not necessary where the third modification is employed that does not embody the interlocking and locating bars 7, but has the 30 equivalents of these bars already located between the brick portions, all attached to a flat nailing

strip. In that case the shingles are assembled merely by nailing them in properly related positions, with the bricks of one strip resting upon the base strip of a lower shingle.

My invention is therefore not limited specifically to the detailed arrangements that are illustrated in the drawing, since various modifications may be made therein without departing from the spirit and scope of the invention as set forth in the appended claims. 5 10

I claim as my invention:

1. A shingle comprising a nailing strip having a plurality of brick-simulating portions connected thereto along the lengthwise edges of the brick portions, said portions being spaced lengthwise from each other by a distance corresponding to the average thickness of a layer of cementing mortar, and one or more interlocking or positioning bars on the nailing strip located intermediate the spaces between the bricks and raised from the nailing strip, the interlocking bars being of the same width as, and being adapted to fit into, the spaces between the spaced brick portions, on an adjoining shingle. 15 20

2. A shingle comprising a nailing strip having a plurality of brick-simulating portions integrally connected thereto, said portions being spaced a predetermined distance from each other, and an element on the nailing strip serving as a positioning bar to guide and locate an adjoining shingle by fitting between similar brick-simulating portions of the adjoining shingle. 25 30

ALBERT HOROWITZ.
